Primary Examiner — Rhea Shields*(74) Attorney, Agent, or Firm* — Peter L. Brewer; Baker Donelson IP Group(57) CLAIM

We claim the ornamental design for a cigarette package, as shown and described.

DESCRIPTION

FIG. 1 is a perspective view for a cigarette package, showing our new design;

FIG. 2 is a front elevation view of the cigarette package of FIG. 1.

FIG. 3 is a back elevation view of the cigarette package of FIG. 1, which is opposite the view of FIG. 2.

FIG. 4 is a right side elevation view of the cigarette package of FIG. 1.

FIG. 5 is a left side elevation view of the cigarette package of FIG. 1, which is a mirror image of the view of FIG. 4.

FIG. 6 is a top or plan view thereof.

FIG. 7 is a bottom view thereof.

FIG. 8 is an exploded perspective view of thereof, showing the package in an open configuration with a liner and top portion removed from the package; and,

FIG. 9 is another perspective view of the cigarette package of FIG. 1. Here, the hinged lid of the package is again opened, exposing an integral liner.

Certain lines are presented herein to provide shading in order to provide a fuller understanding of the cigarette package. Such shading lines form no part of the claimed design.
